UNITED STATES PATENT OFFICE.

FOLKE W. WESTON, OF NEW YORK, N. Y., ASSIGNOR TO F. WESEL MANUFACTURING COMPANY, OF BROOKLYN, NEW YORK, A CORPORATION OF NEW YORK.

PLATE-HOLDING DEVICE.

1,108,646.

Specification of Letters Patent. Patented Aug. 25, 1914.

Application filed March 31, 1911. Serial No. 618,051.

To all whom it may concern:

Be it known that I, FOLKE W. WESTON, a citizen of the United States, and a resident of the borough of Brooklyn of the city of New York, in the State of New York, have invented certain new and useful Improvements in Plate-Holding Devices, of which the following is a specification.

The invention relates to new and useful improvements in devices for positioning and holding printing plates and particularly to such as are employed for supporting and holding curved plates.

As showing a specific embodiment of the invention reference is made to the drawings forming a part of the specification in which—

Figure 1 is a partial plan view of a device embodying the invention. Fig. 2 is a partial vertical section on line 2—2 of Fig. 1. Fig. 3 is a partial end view of the device illustrated in Fig. 1. Fig. 4 is a plan view of the plate clamping or engaging member which can be positioned in different places in the slotted portions shown in Figs. 1 to 3. Fig. 5 is a side view of the same showing the hand setting tool in operative position therein. Fig. 6 is a detail view of the hand setting tool. Fig. 7 is an end and sectional view of the screw threaded operating means. Fig. 8 is an end view of the plate clamping and engaging member with a portion of the hand setting tool shown in operative position therein and a section of the base indicated by dotted lines. Fig. 9 is a side elevation partly in section of a modified form of that shown in Fig. 5. Fig. 10 is still another modified form. Fig. 11 is an enlarged transverse vertical sectional view taken through one of the screw threaded operating means showing its normal position in one of the slotted portions. Figs. 12 and 13 show in plan and partial sectional view the spring construction for resiliently supporting the screw operating member in normal position in the slotted portions. Fig. 14 is a partial sectional view of the base or supporting member for the hook showing the thread cutting means in place thereupon. Fig. 15 is a view of a thread cutting means on the side carrying the tap. Fig. 16 is a side elevation of the thread cutting means with the work or base indicated by dotted lines showing the relative positions which they occupy when the

threading operation is being carried out. Fig. 17 is a partial sectional view of the tool taken on the line 17—17 of Fig. 16 looking in the direction of the arrows. Fig. 18 shows the relative position of the cutting tool and the work during the roughing cut operation. Fig. 19 shows the relative position of the cutting tool and the work when the finishing cut is being made.

In the particular device illustrated the base is a cylindrical member 1 having formed therein a series of parallel spiral slots 2 which make substantially an angle of 45° with the axis of the cylinder. At each side of the slotted portions are overhanging portions 3 on the lower adjacent sides of which are formed sections 4 of screw threads which are engaged by a screw operating member 5. In the lower portion of each of the slots there are located a series of springs 6, (see Figs. 11-13) which serve as yielding means for normally holding the screw operating means in position in engagement with the sections of the screw threads on the overhanging portions. It will be observed that the lower portion of each of the slots is cut away sufficiently to permit the springs 6 to be depressed whereby the screw operating means can be wholly disengaged from the sections of the screw threaded teeth in a manner to permit free longitudinal movement thereof in the slot without having to engage with the teeth of the overhanging portions. Each of the screw operating means is preferably provided with a series of inwardly extending spaced openings 5^a located at a less distance apart than the distance between the adjacent walls of the overhanging portions 3 whereby the ends of pincers 7 may be inserted to cause the depressing of the spring and effect the longitudinal movement of the screw operating means in the slot when desired and at a time when the plate engaging means which will hereinafter be described has been removed.

The plate engaging and positioning means is in reality a clamping member 8 having a jaw 9, and spaced lugs 10 and 11. The width of each of the lugs is preferably substantially the distance between the adjacent surfaces of the overhanging portions 3 so that the clamping member can be removed to and from the base by a movement transversely relative thereto when not held

in operative position on the screw operating means.

In the form shown in Fig. 5 a slotted pin 12 is utilized as a means for holding the screw operating means in place between the lugs but it is obvious that in place of this construction a pin or projection 13 on one of the lugs might be provided as shown in Fig. 9 or a structure combining the features 10 above referred to in respect to Figs. 5 and 9 might be utilized as can be seen in Fig. 10. For example in the last figure it will be observed that the projection 14 is carried on the lug 10 and that a pin 12 is also 15 utilized for holding the screw member positively in place. In the form shown in both Figs. 9 and 10 the distance between the lugs should be an amount at least equal to the sum of the overall dimension of a screw 20 operating means and the length which the projections 13 or 14 extend from the inner surface of the lugs in order to permit the removal of the plate engaging or clamping member from the base by transverse move- 25 ment when not held in operative position relative to the screw operating member 5. In both of these forms the projections 13 and 14 should be located between the screw operating means and that lug which is opposite the plate engaging surface of the clamping or engaging member in order that the hold between the screw means and the lug will be more positive with the tightening of the clamping surface upon the work.

In all of the forms illustrated the movement of the screw operating member 5 is effected by the hand setting tool 16 whose gear teeth 17 are constructed so that they can mesh with the gear teeth 18 on the screw 40 operating member.

From an inspection of Figs. 1, 2 and 3 it will be apparent that there are formed upon the adjacent overhanging portions which define the sides of the slotted portion, a series of teeth which are the sections of screw threads all located a certain distance from the outer surface of a cylindrical or curved body and in Figs. 14 to 19 there is disclosed the tool or apparatus by which these teeth 50 have been formed. The tool utilized comprises a main member or frame 20 having a short tap 21 rotatably mounted in the ears 22 secured to the central portion thereof. There is also secured at each end of the frame guide members 23 arranged to rest in slotted portions located upon opposite sides of the slotted portion being tapped or subjected to the action of the thread cutting tool. There is also carried by the frame an overhanging guide member 24 arranged to engage the same slotted portion as that which is subjected to the action of the tap or thread cutting tool.

As the teeth to be formed are upon a curved surface or at least upon a surface

which will not permit the tap to travel upon a straight line, it is preferable to make the tap comparatively short in order that it may follow the curvature desired and there is therefore preferably employed a tap for carrying out a roughing operation and a tap preferably of the same outside diameter as the roughing out tap for performing the finishing cut.

In Fig. 18 can be seen the position which the tap occupies in performing the roughing out operation and in Fig. 19 it will be observed that a thin filler 26 clearly shown in Figs. 16 and 18 between the frame and the lugs 22 has been removed in order to bring the axis of the finishing tap nearer to the portion of the frame which is engaged by the surface of the work, or in other words to bring and to hold the tap in a position where its axis will be closer to the work than that occupied by the roughing out tap, and in this manner position the tap correctly for carrying out the finishing operation.

It is obvious that various forms and modifications may be made without departing from the spirit and scope of the invention.

I claim as my invention:

1. In a device of the class described the combination of a base having a slotted portion, a plate engaging member having ears entering the same which member can be removed from the base by a transverse movement relative thereto and an operating screw in the slotted portion engaging teeth therein, the screw operating member being normally supported and held in place by spring means carried by the base, the slotted portion being of such shape that by pressing the screw member against the spring means the former can be moved longitudinally in the slotted portion from one position to another.

2. In a device of the class described the combination of a base having a slotted portion, a plate clamping member having ears entering the same which member can be removed from the base by a transverse movement relative thereto an operating screw held in place in the slotted portion and engaging teeth therein, the screw operating member being normally held in place by spring means carried by the base, the slotted portion being of such shape and the spring means of such construction that by pressing the screw member against the spring means it can be moved longitudinally in the slotted portion from one position to another and be resiliently supported in said positions, the screw being provided with inwardly extending holes.

3. In a device of the class described the combination of a base having a slotted portion, a plate engaging member having ears entering the same which member can be removed from the base by a transverse move-

ment relative thereto and an operating screw in the slotted portion and normally held in place by springs carried by the base, the slotted portion being of such shape that by pressing the screw against the spring it can be moved longitudinally in the slotted portion from one position to another and be resiliently supported in said positions, the screw being provided with inwardly extending holes which are spaced a distance less than the distance between the adjacent faces of the slot, the slotted portion being curved and provided with portions of screw threaded teeth arranged along overhanging portions of the slotted portion.

4. The combination of a cylindrical base having a curved slotted portion provided with screw threaded portions formed integral with the base and a plate engaging member operated by a screw member in the slotted portion which engages the screw threads therein.

5. The combination of a cylindrical base having spiral slots therein which are provided with overhanging portions having sections of screw threaded teeth extending along the same and a register hook screw operating means in said slot.

6. The combination of a cylindrical base having spiral slots therein which are provided with overhanging portions having sections of screw threaded teeth extending along the same and a screw operating means in said slot, the slotted portion being so shaped that the screw operating means therein can be moved transversely sufficient

to cause disengagement of the screw threads with the teeth and permit free longitudinal movement of said screw operating means from one position to another along the slot. 40

7. The combination of a cylindrical base having spiral slots therein which are provided with overhanging portions having sections of screw threaded teeth extending along the same and a register hook screw operating means in said slot, the slotted portion being so shaped that the screw operating means therein can be moved transversely sufficient to cause disengagement of the screw threads with the teeth and permit free longitudinal movement of said screw operating means from one position to another along the slot, the slotted portion being provided with a resilient means for normally holding the screw operating means in engagement with the teeth. 50

8. The combination of a screw operating member and a plate engaging member having spaced lugs one of which is provided with an inwardly extending projection for holding the engaging member in place upon the operating member, the projection extending from a surface of said lug which is opposed to a plate engaging surface of the plate engaging member. 60

This specification signed and witnessed this 28th day of March A. D., 1911.
